United States Patent Office

Des. 204,136
Patented Mar. 22, 1966

204,136

TERMINAL HOUSING

Joseph K. Schaefer, 2107 N. Beachwood Drive,
Hollywood, Calif.

Filed Mar. 5, 1965, Ser. No. 84,104

Term of patent 14 years

(Cl. D26—1)

FIG. 1.

FIG. 4.

FIG. 2.

FIG. 5.

FIG. 3.

FIGURE 1 is a top plan view of a terminal housing, showing my new design.

FIGURE 2 is a side elevational view of the terminal housing.

FIGURE 3 is a bottom view.

FIGURE 4 is an end elevational view taken along line 4—4 of FIGURE 1.

FIGURE 5 is an elevational view of the opposite end from that shown in FIGURE 4.

I claim:

The ornamental design for a terminal housing, substantially as shown.
